UNITED STATES PATENT OFFICE

THOMAS W. HUNTER, OF ALHAMBRA, CALIFORNIA

OIL BURNER

Application filed September 10, 1929. Serial No. 391,659.

This invention relates to an oil burner and particularly pertains to a burner of the open pan type as generally indicated in Patent No. 1,426,874, issued to me on the 22nd day of

5 August, 1922.

It is the principal object of the present invention to provide a burner structure substantially adapted for use with liquid hydrocarbons and by which a thorough combustion of the hydrocarbons may be brought about without the objectionable accumulation of carbon deposits on the parts of the burner. This device has been especially designed for use in connection with hot air heaters, and 10 particularly in connection with heater structures used in poultry houses and the like, where it is desired to automatically maintain the air at a constant temperature and to regulate the flow of oil to the burner under thermodynamic control to maintain the desired temperature.

In designing a burner of this type it is necessary to insure satisfactory continuous combustion of the hydrocarbons with a minimum deposit of carbon on the parts which would tend to decrease the heating efficiency of the burner and also make it possible in some instances for the liquid fuel, or portions of it, to escape from the burner without combustion. A burner of the design here shown produces a thorough mixture of the liquid fuel and air supporting combustion so that irrespective of the rate of flow of the fuel from the burner the combustion will be thorough and the fuel will burn with a clear bright flame.

The present invention contemplates the provision of a liquid fuel supply pipe having an upturned discharge end in communication 40 with a fuel well over the sides of which the oil may flow into a combustion compartment within which the fuel gasifies and intimately contacts with air supporting combustion to produce proper combustion thereof.

45 The invention is illustrated by way of example in the accompanying drawings in which:

50 Figure 1 is a view in vertical section through the burner showing the construction of the burner parts and circulating means for

the liquid fuel and the air supporting combustion.

Fig. 2 is a view in plan showing the design of the burner.

Fig. 3 is an enlarged view in transverse 55 vertical section through the burner with the cover removed therefrom.

Fig. 4 is a view in plan showing the base element of the burner and the oil pans and air ducts.

Fig. 5 is a fragmentary view in vertical section taken through the assembled structure on the lines 5—5 of Fig. 2 of the drawings and showing the relation of the cover cap to the segmental fuel pans and the manner in 60 65 which air flows in relation thereto.

Referring more particularly to the drawings, 10 indicates the base structure of a heating unit with which the present invention is concerned. The heat chamber 11 is provided 70 with an intermediate air passageway 12 through which air may flow to the burner which burner is indicated at 13 in the drawings.

The burner comprises a base portion 14 75 seated upon the floor 15 of the heating compartment and circumscribing an opening 16 in the floor. This base includes an upwardly extending circular side wall 17 of substantially the same inside diameter as the diameter of 80 the opening 16 through the floor. At different points along the circumference of the base fastening lugs 18 are provided carrying screws 19 by which the base may be secured to the floor 15. As clearly shown in Fig. 4 of 85 the drawings segmental pans 20 and 21 extend inwardly from the wall 17 of the base and are formed integral with fire and gas directing baffle walls 22 and 23, which extend upwardly from a disc-shaped floor 24 of the 90 burner base as more clearly shown in Fig. 1.

The pans 20 and 21 are bounded on their opposite sides by vertical wall members 25 and 26. These members are of a lesser height than that of the retaining walls 22 95 and 23, as well as the circumscribing base wall 17. Formed as a continuation of the walls 25 and 26, and extending inwardly and radially beyond the ends of the arcuate retaining walls 22 and 23 are baffle walls 27 100

which terminate at the outer edge of an annular oil groove 28 formed in the floor 24 of the combustion chamber 29 of the burner structure.

5 The groove 28 is concentric with the center of the base 14 and is bound along a part of its outer edge by the arcuate retaining walls 22 and 23. These walls do not, however, continually circumscribe the center of the 10 burner and thus provide throats 30 and 31 between the baffle walls 27 and across the groove 28 upon diametrical sides of the burner. The inner side of the groove 28 is defined by circular rib 32 which extends 15 upwardly, is spaced from and circumscribes a tubular well 33 into the bottom of which liquid fuel is delivered and over the upper lip of which fuel may ebullate. The oil well 33 has a downwardly extending lip 34 into 20 which a pipe connection 35 is threaded. This pipe is fitted with an elbow and liquid fuel feed pipe 36. By examining the structure it will thus be evident that oil may flow upwardly through the well 33 and flow over the 25 edges thereof into a groove 37 circumscribing the well and then over the rib 32 into the groove 28.

Disposed above the base structure 14 and 30 acting as a cover therefor, as well as co-operating therewith to form air circulating ducts, is a cover structure 38. This structure is disc shaped having notches 39 in its opposite sides to register with upwardly projecting lugs 40 formed on the edge of the circular 35 flange 17 of the base 14. These members properly position the cover with relation to the base and parts thereof. Formed centrally of the cover is a rectangular opening 41, which is disposed directly over the mouth 40 of the oil well 33, although of considerably greater area than the diameter of the well. Disposed upon opposite sides of the opening and formed as a part of the cover are two air 45 passageways 42 and 43 which are arcuate in shape and extend along the major sides of the rectangular opening 41. These passageways are offset vertically from the upper face of the cover and occupy the area directly above the segmental oil pans 20 and 21, and 50 extend at opposite ends slightly therebeyond.

By reference to Figs. 4 and 5 it will be seen that the opposite ends of the arcuate ducts 42 and 43 in the cover 38 overhang the segmental air passageways 44 and 45 in the base 14, and extend along and between the walls 17 and 22 of the base and are terminated by the walls 25 and 26 of the oil pans 20 and 21.

In the operation of the present invention 55 liquid fuel is delivered through the pipe 36 to the well 33. This well will fill and thereafter the oil will overflow the top edge thereof. This oil will then flow downwardly in a uniform stream along the outer side wall 60 of the well 33 and into the groove 37, circum-

scribing the well. It will then flow outwardly over the circular rib 32 into the groove 24. The rib will act as a baffle for the outwardly flowing liquid which is radiating in its flow from the wall of the well 33 and will thus insure that the flow of the liquid will be slow and that the liquid will have an opportunity to properly ignite and to have thorough combustion. The liquid is confined in its further outward flow due to the presence of the walls 22 and 23 which circumscribe the floor 24. This liquid may however flow out into the pans 20 and 21 and expose an additional surface area of liquid to combustion. A drain pipe 46 extends into the bottom of the pan 21 at a point between the outer wall 17 and the baffle rib 47 shown in Fig. 4. This rib retards the flow of liquid from the pans and the floor of the burner and insures that a relatively large area of liquid surface will be maintained, and that a resulting large combustion surface will be produced.

It is understood that the oil is ignited either in the pans or in the well 33 and that as the burner heats the liquid will gasify and its combustion will be more thoroughly effective. The lower portion or base of the burner is covered with the cap structure previously described and thus insures that air may pass into the burner through the passageways 44 and 45 and then upwardly between the outer wall 17 of the base and the outer walls 22 and 23 of the burner structure as indicated by the arrows in Figs. 1 and 5. The air will then pass upwardly into the arcuate air ducts 42 and 43 of the cap as clearly shown in Fig. 5 and will pass over the radial walls 25 and 26 at opposite sides of the oil pans 20 and 21. The air will then flow downwardly between these walls and inwardly toward the well 33 while passing over the surface of the oil accumulated on the floor of the pans 20 and 21 and on the floor 24 of the burner.

As the air passes inwardly as confined by the converging side walls 25 and 26, it will pass through the restricted openings 30 and 31, thereby giving it increased velocity, and will thereafter expand and pass around the projecting portions 27 of the walls 25 and 26, in a manner to produce an eddy current traveling in a horizontal plane over the surface of the oil and to insure that the air will be uniformly and thoroughly mixed with the gaseous fuel and liquid fuel itself. By this means efficient combustion is insured and the products of combustion will pass upwardly and outwardly through the opening 41 in the cover 38.

A comparison of this burner with other burners of similar type has proven that due to the manner in which the air is directed in the burner compartment and agitated, and caused to co-mingle with the liquid fuel and its gaseous vapors, a relatively high degree 125

of efficiency is obtained, and a burner is produced which insures a sufficiently thorough combustion to make it unnecessary to clean the burner except after long periods of use.

5 While I have shown the preferred form of my invention as now known to me, it will be understood that various changes may be made in the combination, construction and arrangement of parts by those skilled in the 10 art, without departure from the spirit of the invention as claimed.

Having thus described my invention, what I claim and desire to secure by Letters Patent is:

15 1. A burner comprising an annular frame, a plurality of segmental pans integral with said frame, a fuel well intermediate of said pans, an annular basin surrounding said well and being integral with said pans, converging 20 walls banding said pans, arcuate air passages within said frame and positioned to the side of said pans, a baffle wall between said passages and said basin, said baffle wall terminating in a plane intersected by the walls 25 bounding said pans, a cover for said burner, grooves in said cover, said grooves being positioned to overhang said passages and said pans whereby air may be conducted from said passages to said pans to promote combustion 30 within said burner.

2. An oil burner comprising a base member having a central annular combustion chamber, a fuel supply pipe communicating centrally thereof, a tubular wall projecting upwardly from said fuel supply pipe and disposed concentrically with relation to the central wall of the combustion chamber, a circular side wall carried by the base and circumscribing the combustion chamber, said 35 wall being in spaced relation thereto, a pair of segmental fuel pans disposed upon opposite sides of the combustion chamber and spanning the space between the circular side wall and the outer edge of the combustion 40 chamber, the opposite sides of said pans being bounded by vertical radial wall sections of lesser width than the side wall, the space between said walls at opposite sides of the pans being opened between the combustion 45 chamber and the side walls to permit a free flow of air upwardly through the base, and a cover for said burner having its major portion in a plane with the upper edge of the side wall and arcuate offset ducts projecting 50 above said plane in the area of the segmental pans whereby air may float upwardly over the vertical walls of said pans and thence 55 radially into the combustion chamber, the center of said cover plate being opened to permit the flame to pass upwardly through said cover plate and from the burner.

3. An oil burner comprising a base member having a central annular combustion chamber, a fuel supply pipe communicating centrally thereof, a tubular wall projecting

upwardly from said fuel supply pipe and disposed concentrically with relation to the central wall of the combustion chamber, a circular side wall carried by the base and circumscribing the combustion chamber, said 70 wall being in spaced relation thereto, a pair of segmental fuel pans disposed upon opposite sides of the combustion chamber and spanning the space between the circular side wall and the outer edge of the combustion chamber, the opposite sides of said pans being bounded by vertical radial wall sections of lesser width than the side wall, the space between said walls at opposite sides of the pans being opened between the combustion 75 chamber and the side walls to permit a free flow of air upwardly through the base, a cover for said burner, having its major portion in a plane with the upper edge of the side wall and arcuate offset ducts projecting 80 above said plane in the area of the segmental pans whereby air may float upwardly over the vertical walls of said pans and thence radially into the combustion chamber, the center of said cover plate being opened to permit the flame to pass upwardly through said cover plate and from the burner, arcuate grooves 85

upwardly from said fuel supply pipe and disposed concentrically with relation to the central wall of the combustion chamber, a circular side wall carried by the base and circumscribing the combustion chamber, said 135 wall being in spaced relation thereto, a pair of segmental fuel pans disposed upon opposite sides of the combustion chamber and spanning the space between the circular side wall and the outer edge of the combustion chamber, the opposite sides of said pans being bounded by vertical radial wall sections of lesser width than the side wall, the space between said walls at opposite sides of the pans being opened between the combustion chamber and the side walls to permit a free flow of air upwardly through the base, a cover for said burner, having its major portion in a plane with the upper edge of the side wall and arcuate offset ducts projecting above said plane in the area of the segmental pans whereby air may float upwardly over the vertical walls of said pans and thence radially into the combustion chamber, the center of said cover plate being opened to permit the flame to pass upwardly through said cover plate and from the burner, arcuate grooves

extending from the wall of one segmental pan to the wall of the other and being bounded at the inner edge by the relatively low wall of the combustion chamber whereby oil
5 accumulating on the floor of the combustion chamber may overflow into these grooves, and a rib extending upwardly from the floor of one of the segmental pans and transversally thereof to permit a predetermined
10 quantity of fuel to be impounded upon the floor of the combustion chamber within the arcuate grooves and upon the floors of the segmental pans.
